GAME APPARATUS

Arthur Percival Masters, Wellington, New Zealand, assignor of one-half to Henry Vaughan Clere Welsby, Wellington, New Zealand

Application January 21, 1939, Serial No. 252,058
In New Zealand December 14, 1935

10 Claims. (Cl. 273—35)

This is a continuation-in-part application of above inventor's United States application, Serial No. 114,477, filed December 5, 1933.

The present invention relates to game apparatus, and provides improved apparatus for enabling the equivalent of a game of golf to be played in restricted spaces without restraint as regards the power put into strokes, provision being made for indicating or recording the power 5 value of the strokes imparted to a ball, and also for putting.

The main object of my invention is to provide game apparatus of the character mentioned which will make it possible to simulate the playing 15 of complete games of golf, etc., by including means for indicating the score attained by a player.

Another object is to provide such a game with indicating means which will account good strokes 20 and bad by making it possible to subtract poor strokes from a score which represents one or more proper strokes or plays.

A further advantage is to have indicating means of such character as to allow more than 25 one player to use the game and in fact, allow two players to play against each other.

Further objects and the other advantages of the invention will appear more fully hereinafter as this specification pursues.

30 The improved apparatus provided by the invention, comprises a base; a captive ball adapted to travel along the latter; a tee from which said ball is struck and a trapping screen or curtain at opposite ends of said base, and between which 35 ends said ball travels, and particularly means actuated as a result of the ball travelling from the tee, for score indicating or recording the power value of the stroke imparted to the ball.

In order to introduce a competitive element 40 into a game played on the apparatus, separate score indicating or recording means, each capable of use without affecting the other, are provided, also in order that the game shall be so attractive and realistic as to invite use, the score indicating or recording means are marked or gotten up to represent fairways and holes of varying 45 lengths, to represent a full course.

In the accompanying drawings in conjunction 50 with which the invention will be more particularly described:

Figure 1 is a plan view and

Figure 2 is a longitudinal sectional view of the improved apparatus, taken on line II—II in 55 Figure 1,

Figure 3 a part plan view enlarged of the indicating or recording means employed,

Figure 4 an elevation of the parts shown in Figure 3,

Figure 5 a part perspective view showing the 5 trapping screen or curtain,

Figure 6 a cross sectional view of the indicating or recording means illustrating a modification.

In a practical embodiment of the invention, 10 the apparatus comprises a more or less conventional base 1, of any suitable material and size, in or on which is secured so as to extend lengthways of the base, a wire or rod 2, having slidably secured thereto a flexible connection 3 of a captive ball 4, so that the latter although always remaining secured to the base 1, is free to travel 15 lengthways thereof.

The wire or rod 2 can if desired, be accommodated in a recess or slot 5 in or on the base 1. 20

At one end of the base 1, there is provided a spring or resilient tee 6 in line with the wire or rod 2, while at the other end of the base 1 and also in line with the wire or rod 2, a screen or curtain 7 of flexible material, such as canvas or the like, 25 is provided for trapping the ball 4 following the latter being struck from the tee 6, by means of a golf club used in the ordinary manner of play.

The screen 7 is mounted between springs 8 formed from wire of suitable gauge, and preferably of the form comprising a pair of legs joined to each other at their upper ends.

The springs 8 are mounted vertically one at each side of the base 1 and opposite each other, one leg of each spring being preferably longer 35 than the other leg for pivoting to the base 1 at 8a, the other legs being left free.

The screen 7 has upper and lower cross rods 9, 10 respectively, the lower cross rod 10 being secured to the lower ends of the free legs of the 40 springs 8, while the upper rod 9 is attached at its ends to the free legs of the springs 8 so as to be slideable up and down same.

In securing the springs 8 to the base 1, they 45 are set so as to tend to pull away from each other, so that when the upper or sliding rod 9 of the screen 7 is raised on the free legs of the springs 8, the tension or pull exerted on said rod 9 keeps the latter in the raised position.

By pivoting the springs 8 to the base 1, they 50 together with the screen 7, can be folded down on the base for package, stowage or transport purposes, stays or arms 11 extending from the pivoted legs of said springs 8 being provided to engage catches 11a on the base 1 when the springs 55

8 are raised and so retain the latter in the correct position when the apparatus is being used.

The wire or rod 2 to which the captive ball 4 is slidably attached, is connected at one end to the lower cross rod 10, secured to the lower ends of the free legs of the springs 8, used for supporting the screen or curtain 7, a buffer or buffers 12 of rubber or other suitable material being placed on said wire or rod 2 adjacent the said rod 10, and upon the captive ball 4 being struck from the tee 6, the impact of the ball 4 with the screen or curtain 7, causes the rod or wire 2 to be jerked forward and the full value of the stroke made by the player playing the ball 4, to be transmitted via said wire or rod 2, to the indicating or recording means, as will be described, the buffer or buffers 12, acting as a check during rebound of the rod or wire 2, against the base 1.

The wire or rod 2 passes below a retainer 13 located in front of the resilient tee 6, and is bent upwards and then downwards to provide an upward kink as at 2a prior to reaching the lower cross rod 10 of the screen or curtain 7, the end of the base 1 being grooved or recessed at 1a to accommodate the end of the wire or rod 2 and the buffer or buffers 12 thereon.

At the end of the base 1 at which the tee 6 is located, the wire or rod 2 passes below a cover plate 15 and said tee 6, and is provided with a sliding extension 16 having its free end formed or provided with a loop 17, adapted to be engaged by an arm 18 on a rod 19 which extends across the base below the tee 6, said rod 19 having its ends journalled in bearings on the base 1, as, for example, by being extended into the sides of the latter, adjacent which further arms 20 are provided on the cross rod 19.

The tee 6 can comprise a piece of fibre board or other suitable material attached at one end 40 to the base 1 so as to normally extend upwards therefrom at its free end in a direction facing towards the screen or curtain 7, said tee 6 being provided at its highest point with a seat 6a for the captive ball 4, and also containing an opening 21 to give access to the interengaging loop 17 and arm 18 situated below it.

An important feature is the connection of the captive ball 4 to the longitudinal wire or rod 2 in advance of the ball 4 when the latter is to be struck, and in order to ensure this condition always being present when required, the ring 3a of the flexible connection 3 between the wire or rod 2 and the ball 4, is placed on said wire or rod 2 between the retainer 13 and the screen or curtain 7, so that said ring 3a and the flexible connection 3 are always in advance of the ball 4 when the latter is in position on the tee 6 for being struck in play, this advanced position of the flexible connection 3 and the kinking of the wire or rod 2, as at 2a, having the effect of minimizing wear and tear on the ball 4 and the flexible connection 3 and associated parts.

The means for indicating or recording strokes and for indicating greens are provided at each 65 side of the base 1 adjacent the longitudinal edges thereof, and mainly comprise endless cords 22 which pass around pulleys 23, while said cords 22 have representations 25 in miniature of golf balls attached thereto, the portions of the sides 70 of the base 1 over which the representations 24 travel, being at the same time marked to represent numbered greens and also being graduated or calibrated in yards or as desired.

The pulleys 23 of the indicating or recording 75 means, located at the end of the base 1 at which

the tee 6 is located, have secured on their spindles arms 25, preferably balanced or weighted and adapted to revolve through openings or slots 26 in the sides of the base 1, said arms being capable of being set in front of the arms 20 at the 5 ends of the cross rod 19 which passes below the tee 6, so that with the arm 18 at the centre of said cross rod 19 engaged with the loop 17 connected to the wire or rod 2, movement of the latter endways caused by the captive ball 4 being 10 struck from the tee and hitting the screen or curtain 7, results in operation of whichever indicating or recording means is being used, and simultaneous indication or recording of the value of the stroke made.

Also in the base 1 are located holes 27 into which free balls can be putted from marked putting points or positions indicated preferably by shallow depressions 28 in the base 1.

A player places the captive ball 4 on the tee 6 20 and drives it towards the screen or curtain 7, which, on being struck by the ball 4, is bulged outwards and draws down the upper cross rod 9, causing the ball 4 to be trapped at the same time operating the indicating or recording means 25 as aforesaid, and causing the endless cord 22 of the indicating or recording means being used to travel so that the indicator represented by the ball 24 in miniature on the cord 22, moves along the marked portion or side of the base 1, a distance relative to the strength or force of the stroke, the player making sufficient strokes to take the ball indicator 24 to a space representing a green, following which the hole is finished by putting a free ball into one of the holes 27 in 35 the base 1 before referred to.

Provision is made on the indicating or recording means for any desired number of greens, all the putting in respect of each of which is done with a free ball on the base 1.

The endless cords 22 to which the ball indicators 24 are attached, can run in grooves 30a in the edges of strips 30 on the sides of the base 1, so as to be concealed or be partly concealed, the portions of the base 1 over which the ball indicators 24 travel being marked with measurements or/and other markings and ornamentation to represent greens, holes, bunkers, rough and other features appropriate to the game of golf.

The lower edge of the screen or curtain 7 can 50 be cut away as at 1a, and the wire or rod 2 can be connected to the lower rod 10 of said screen or curtain 7 so as to slide therealong, with the result that "pulling or slicing" the ball 4 is indicated and the power value of the stroke is also 55 reduced accordingly.

An indicator 29 slidable along the marked portions of the indicating or recording means is provided and is capable of being set to show which hole is being played to.

In order to provide for reverse or backward travel of the ball indicators 24, such as when the latter over-run spaces representing greens on the marked portions of the base 1, slotted sliding plates 33 are fitted one to each side of the base 65 1, adjacent the rotary arm 25, said plates 33 having lugs or projections 31, 32 extending therefrom.

The lugs 31, 32 of a plate 33, are spaced so that when the plate 33 is slid forward or towards the 70 trapping screen or curtain 7, lug 32 supports the adjacent arm 26 on the rod 19 in a rearwardly inclined position behind the arm 25, when the latter is set for use at right angles to the edge or side of the base 1, with the result that upon a 75

stroke being made by striking the ball 4 from the tee 6 into the curtain or screen 7, the arm 20 strikes the back of the arm 25 and causes the ball indicator 24 to travel forward, which is in the direction indicated by the arrow.

To obtain reverse travel of the ball indicator 24 when it is necessary to cause the same to return to a space representing a green, the plate 33 is slid in a direction from the screen or curtain 7, to bring lug 31 into a position in which it will support the arm 20 in a forwardly inclined position in front of the arm 25.

In this position of the arm 20, the centre arm 18 of the rod 19, also inclines forward or towards the screen or curtain 7, and upon the latter being struck by the ball 4 driven from the tee 6, the loop 17 is pulled forward and jumps over the arm 18 and upon said loop 17 moving backwards due to the rebound of the screen or curtain 7, it strikes the arm 18 backwards so that arm 20 also moves backwards and causes arm 25 to turn in the direction necessary to make the ball indicator 24 travel in the reverse direction to that indicated by the arrow.

Having now fully described my invention, I claim:

1. In a game apparatus, indicating means for cumulatively indicating the various successive drives imparted to a ball adapted to be projected toward a screen, comprising a movably supported rod-like member having a screen connected to one end thereof, said rod-like member being longitudinally movable in response to impacts of the ball with said screen, a cross rod connected transversely of the rod-like member to the other end of the latter member, means actuated by the rod-like member during longitudinal movement of the same and effective to cause rotation of said cross rod, an endless belt mounted on a pair of pulleys and having an indicator, and means connecting said cross rod and endless belt in order to impart movement thereto by rotation of the cross rod caused by longitudinal movement of the rod-like member as a result of impact of the ball with the screen.

2. In a game apparatus, indicating means for cumulatively indicating the successive drives imparted to a ball adapted to be projected toward a screen, comprising a movably supported rod-like member having a screen connected to one end thereof, said rod-like member being longitudinally movable in response to impacts of the ball with said screen, a cross rod connected transversely of the rod-like member to the other end of the latter member, means actuated by the rod-like member during longitudinal movement of the same and effective to cause rotation of said cross rod, a pair of spaced pulleys, an endless belt mounted on said pulleys having an indicator, and adapted to travel on said pulleys, and an arm disposed on said cross rod adapted to engage the arm upon said pulley in order to rotate the latter and thereby cause movement of the belt upon rotation of the cross rod due to longitudinal movement of the rod-like member resulting from impact of the ball with the screen.

3. Indicating means for a game apparatus according to claim 1, wherein the rod-like member is connected at one end thereof to the screen by being slidably secured thereto.

4. Indicating means for a game apparatus according to claim 2, including means for reversing the direction of rotation of the pulleys and thereby reversing direction of movement of the endless

belt when the arm on the one pulley is engaged by the arm on the cross rod.

5. Indicating means for a game apparatus according to claim 2, including manually adjustable means for reversing the direction of rotation of the pulleys and thereby reversing the direction of movement of the endless belt when the arm on the one pulley is engaged by the arm on the cross rod. 5

6. In a game apparatus, indicating means for cumulatively indicating the successive drives imparted to a ball adapted to be projected toward a screen, comprising a movably supported rod-like member having a screen connected to one end thereof, said rod-like member being longitudinally movable in response to impacts of the ball with said screen, a cross rod connected transversely of the rod-like member to the other end of the latter member, means actuated by the rod-like member during longitudinal movement of the same and effective to cause rotation of said cross rod, a pair of endless belts spaced apart in general parallelism, each belt having an indicator and being mounted on a pair of pulleys, and means for selectively connecting said cross rod and either one of said pair of belts at will, to move the selected belt by rotation of the cross rod caused by longitudinal movement of the rod-like member as a result of impact of the ball with the screen. 15 20 25 30

7. In a game apparatus, indicating means for cumulatively indicating the successive drives imparted to a ball adapted to be projected toward a screen, comprising a movably supported rod-like member having a screen secured to one end thereof, said rod-like member being longitudinally movable in response to impacts of the ball with said screen, an endless belt having an indicator movable therewith, intermittent actuating means connecting said rod-like member and said belt in order to move intermittently the belt and thereby also the indicator by successive stages in response to successive impacts of the ball with the screen. 35 40

8. In a game apparatus, indicating means for cumulatively indicating the successive drives imparted to a ball adapted to be projected toward a screen, comprising a movably supported rod-like member having a screen secured to one end thereof, said rod-like member being longitudinally movable in response to impacts of the ball with said screen, a pair of endless belts spaced apart in general parallelism and each having an indicator movable therewith, intermittent actuating means for connecting said rod-like member with either one of said pulleys at will in order to cause movement of the selected belt intermittently by successive stages in response to successive impacts of the ball with the screen. 45 50 55

9. In a game apparatus, indicating means for indicating cumulatively or subtractively at will the successive drives imparted to a ball adapted to be projected toward a screen, comprising a movably supported rod-like member having a screen connected to one end thereof, said rod-like member being longitudinally movable in response to impacts of the ball with said screen, an endless belt mounted on a pair of pulleys and having an indicator movable therewith, intermittent actuating means connecting said rod-like member and said belt in order to move intermittently the belt and thereby also the indicator by successive stages in response to successive impacts of the ball with the screen, and means for reversing the direction of movement of the belt. 60 65 70 75

10. In a game apparatus, indicating means for indicating cumulatively or subtractively at will the successive drives imparted to a ball adapted to be projected toward a screen, comprising a movably supported rod-like member having a screen connected to one end thereof, said rod-like member being longitudinally movable in response to impacts of the ball with said screen, a pair of endless belts spaced apart in general parallelism

and each having an indicator movable therewith, selective intermittent actuating means for connecting said rod-like member with either one of said belts at will in order to cause movement of the selected belt intermittently by successive stages in response to successive impacts of the ball with the screen, and means for reversing the direction of movement of the selected belt. 5

ARTHUR PERCIVAL MASTERS.
